MOLDED PULP FRUIT TRAY

Gilbert R. Chadbourne, Oakland, Maine, assignor to
Keyes Fibre Company, Portland, Maine, a corporation
of Maine

Filed July 11, 1961, Ser. No. 65,878

Term of patent 14 years

(Cl. D58—13)

FIG. 1 is a top plan view of a molded pulp fruit tray embodying my new design;

FIG. 2 is a cross-sectional view taken along the line 2—2 of FIG. 1; and

FIG. 3 is a cross-sectional view taken along the line 3—3 of FIG. 1.

The characteristic feature of my new design resides in the combination, on a tray of the configuration shown, of a pair of gently upwardly rising relatively straight low side walls on opposite sides thereof, a pair of gently upwardly rising relatively straight high end walls, curved gently upwardly rising corner sections, the upper boundary of said corner sections blending smoothly with the upper boundaries of said side walls and end walls in a gently rising continuous manner extending fully around said corner sections, and an interior longitudinally extend-

ing partition of pyramidal configuration and of a height substantially equal to the height of said side walls, substantially as shown.

I claim:

The ornamental design for a molded pulp fruit tray, as shown and described.
